(57) **ABSTRACT**

A double-pintle hinge includes a first pintle, a second pintle, and positioning mechanisms configured to allow the first and second pintles to rotate relative to each other to releasably retain positions. The positioning mechanisms include first and second joining members interconnecting the first and second pintles and sandwiching a first and second cams, a first and second cam followers, and a biasing member. The first cam is coupled to the first pintle. The second cam is coupled to the second pintle. The first and second cam followers are positioned between the first and second cams, and respectively abut the first and second cams, and are movably connected with each other. The biasing member is positioned between the first and second cam followers.

FIG. 7

FIG. 8

POSITIONING MECHANISMS OF DOUBLE-PINTLE HINGE

BACKGROUND OF THE INVENTION

1. Field of the Invention

The present invention relates to a double-pintle hinge and, particularly, to position mechanisms of the double-pintle hinge.

2. Description of the Related Art

TW Pat. No. M452593 shows a double-pintle hinge. The hinge includes positioning mechanisms including a first and second cams and a cam follower disposed therebetween to interact therewith. The first and second cams each have a recess in which the cam follower selectively engages.

In order for the cam follower to movably engage in the recesses of the first and second cams, the size of the cam follower has to be smaller than the recesses. Furthermore, in order to reduce noise caused by interactions between the cams and the cam follower, a rubber sleeve is sleeved on the cam follower. Unfortunately, the sleeve wears out after a long use and wearing rubber bits clog up other components of the hinge.

The present invention is, therefore, intended to obviate or at least alleviate the problems encountered in the prior art.

SUMMARY OF THE INVENTION

According to the present invention, a double-pintle hinge includes a first pintle, a second pintle, and positioning mechanisms configured to allow the first and second pintles to rotate relative to each other to releasably retained positions. The positioning mechanisms include first and second joining members interconnecting the first and second pintles, with each including a first end thereof coupled to the first pintle in a manner that the first pintle is rotatable about a first axis relative to the first and second joining members and a second end thereof coupled to the second pintle in a manner that the second pintle is rotatable about a second axis relative to the first and second joining members. Furthermore, the first and second joining members sandwich a first and second cams, a first and second cam followers, and a biasing member. The first cam is coupled to the first pintle in a manner that the first cam rotates when the first pintle rotates. The second cam is coupled to the second pintle in a manner that the second cam rotates when the second pintle rotates. The first and second cam followers are positioned between the first and second cams, and respectively abut the first and second cams, and are movably connected with each other such that the first cam follower is able to slide on the second cam follower. The biasing member is positioned between the first and second cam followers such that the first and second cam followers are biased axially by the biasing member.

There has thus been outlined, rather broadly, the more important features of the invention in order that the detailed description thereof that follows may be better understood, and in order that the present contribution to the art may be better appreciated. There are additional features of the invention that will be described hereinafter and which will form the subject matter of the claims appended hereto.

In this respect, before explaining at least one embodiment of the invention in detail, it is to be understood that the invention is not limited in its application to the details of construction and to the arrangements of the components set forth in the following description or illustrated in the drawings. The invention is capable of other embodiments and of

being practiced and carried out in various ways. Also, it is to be understood that the phraseology and terminology employed herein are for the purpose of description and should not be regarded as limiting.

As such, those skilled in the art will appreciate that the conception, upon which this disclosure is based, may readily be utilized as a basis for the designing of other structures, methods and systems for carrying out the several purposes of the present invention. It is important, therefore, that the claims be regarded as including such equivalent constructions insofar as they do not depart from the spirit and scope of the present invention.

Further, the purpose of the foregoing abstract is to enable the public generally, and especially the scientists, engineers and practitioners in the art who are not familiar with patent or legal terms or phraseology, to determine quickly from a cursory inspection the nature and essence of the technical disclosure. The abstract is neither intended to define the invention, which is measured by the claims, nor is it intended to be limiting as to the scope of the invention in any way.

Other objectives, advantages, and new features of the present invention will become apparent from the following detailed description of the invention when considered in conjunction with the accompanied drawings.

BRIEF DESCRIPTION OF THE DRAWINGS

FIG. 1 is a perspective view of a double-pintle hinge in accordance with the present invention.

FIG. 2 is a partial, exploded perspective view of the double-pintle hinge of FIG. 1.

FIG. 3 is a partial, exploded perspective view similar to FIG. 2, but taken from a different angle.

FIG. 4 is a cross-sectional view taken along line 4-4 of FIG. 1.

FIG. 5 is a cross-sectional view taken along line 5-5 of FIG. 1 and shows the hinge in a closed position.

FIG. 6 is another cross-sectional view of the hinge of the present invention in a fully open position.

FIG. 7 is an extended cross-sectional view of FIG. 5, showing the hinge in another operating position between the closed and fully open positions.

FIG. 8 is an extended cross-sectional view of FIG. 5, showing the hinge in yet another operating position between the closed and fully open positions.

DETAILED DESCRIPTION OF THE INVENTION

A double-pintle hinge in accordance with the present invention includes a first pintle 20, a second pintle 30, and positioning mechanisms 40 configured to allow the first and second pintles 20 and 30 to rotate relative to each other to releasably retained positions.

The positioning mechanisms 40 include first and second joining members 41 and 42 interconnecting the first and second pintles 20 and 30, with each including a first end thereof coupled to the first pintle 20 in a manner that the first pintle 20 is rotatable about a first axis relative to the first and second joining members 41 and 42 and a second end thereof coupled to the second pintle 30 in a manner that the second pintle 30 is rotatable about a second axis relative to the first and second joining members 41 and 42. The first and second joining members 41 and 42 sandwich a first and second cams 43, a first and second cam followers 44, and a biasing member 45.

The first cam **43** is coupled to the first pintle **20** in a manner that the first cam **43** rotates when the first pintle **20** rotates. The second cam **43** is coupled to the second pintle **30** in a manner that the second cam **43** rotates when the second pintle **30** rotates.

The first and second cam followers **44** are positioned between the first and second cams **43**. The first and second cam followers **44** respectively abut the first and second cams **43**. The first and second cams **43** each have a periphery and include a recess **431** defined by the periphery. The first and second cam followers **44** each have an outer surface and include a protrusion **441** extending from the outer surface. The first and second pintles **20** and **30** have a first releasably retained position in which one of the protrusions **441** is releasably engaged with the respective recess **431**, and a second releasably retained position in which the two protrusions **441** are releasably engaged with the respective recesses **431**. The first and second cam followers **44** are movably connected with each other such that the first cam follower **44** is able to slide on the second cam follower **44**. The first and second cam followers **44** each have a L-shaped body and include a slot **442** recessed in a first extension of the body and a tab **443** protruded from a second extension of the body. The slot **442** and the tab **443** of one of the first and second cam followers **44** respectively engage with the tab **443** and the slot **442** of the other of the first and second cam followers **44** when the first and second cam followers **44** are connected. The protrusion **441** on each of the first and second cam followers **44** is located on the first extension of the body thereof. The first and second joining members **41** and **42** include a first projection **413** and a second projection **413** extending therebetween. The first and second projections **413** are defined by two walls of one of the first and second cam followers **44**. The first and second cam followers **44** are sandwiched between the first projection **413** and the second projection **413**. The second extension of the body of the first cam follower **44** is movable and abuts the first projection **413**. The second extension of the body of the second cam follower **44** is movable and abuts the second projection **413**. Each of the first and second cam followers **44** includes the body thereof having two lateral edges and includes the protrusion **441** extending therefrom located between the two lateral edges. The two lateral edges of each of the first and second cam followers **44** are sandwiched between inner surfaces of the first and second joining members **41** and **42**. The two lateral edges of each of the first and second cam followers **44** are defined by two lateral sides of the first extension as well as two lateral sides of the second extension.

The biasing member **45** is positioned between the first and second cam followers such that the first and second cam followers **44** are biased axially by the biasing member **45**. The biasing member **45** is a coil spring. The first and second cam followers **44** each include a cavity to hold a distal end of the biasing member **45**. As such, the biasing member **45** is stably positioned between the first and second cam followers **44**.

The first and second pintles **20** and **30** each include a plurality of elastomeric members **50** engaged therewith. The plurality of elastomeric members **50** on the first pintle **20** are restrained between one of the first and second joining members **41** and **42** and a first retainer **60** and the plurality of elastomeric members **50** on the second pintle **30** are restrained between one of the first and second joining members **41** and **42** and a second retainer **60**. The first

retainer **60** and the first pintle **20** are in thread engagement. The second retainer **60** and the second pintle **30** are in thread engagement.

The double-pintle hinge **10** is a hinge for electronic devices and, particularly for an electronic device including a first member and a second member. As such, the first and second members are pivotally coupled to each other by the double-pintle hinge **10**. Furthermore, one of the pintles **20** and **30** coupled to the first member rotates when the first member is pivoted. Likewise, the other of the pintles **20** and **30** coupled to the second member rotates when the second member is pivoted. The first pintle **20** is rotatable about a first axis. The second pintle **30** is rotatable about a second axis, which is parallel to the first axis.

The double-pintle hinge **10** has a fully open position and a closed position defined from two releasably retained positions of the first and second pintles **20** and **30**. The first and second pintles **20** and **30** are limited to rotate between the fully open position and the closed position. The first and second pintles **20** and **30** respectively have an outer surface and include a first ridge **21** and **31** extending from the outer surface. The first joining member **41** has an outer surface and includes a second ridge **411** extending from the outer surface. The double-pintle hinge **10** in the fully open position includes the first ridge **21** of one of the first and second pintles **20** and **30** releasably engaged with the second ridge **411**. The first ridge **21** of the respective first and second pintles **20** and **30** has two distal ends spaced radially and a curved outer edge joining the two distal ends. In addition, the outer surface of the first joining member **41** includes a third ridge **412** extending therefrom adapted to releasably engage with another first ridge **31**. In view of the forgoing, the first and second cam followers **44** can move stably, thereby avoiding unwanted vibration and making noise. As set forth, the first and second cam followers **44** are positioned between the first and second cams **43**, and respectively abut the first and second cams **43**, and are movably connected with each other such that the first cam follower **44** is able to slide on the second cam follower **44**. Each of the first and second cam followers **44** includes the lateral edge

The foregoing is merely illustrative of the principles of this invention and various modifications can be made by those skilled in the art without departing from the scope and spirit of the invention.

What is claimed is:

1. A double-pintle hinge comprising:
a first pintle;
a second pintle; and
positioning mechanisms configured to allow the first and second pintles to rotate relative to each other to releasably retained positions comprising:
first and second joining members interconnecting the first and second pintles, with each including a first end thereof coupled to the first pintle in a manner that the first pintle is rotatable about a first axis relative to the first and second joining members and a second end thereof coupled to the second pintle in a manner that the second pintle is rotatable about a second axis relative to the first and second joining members, and sandwiching a first and second cams, a first and second cam followers, and a biasing member;
the first cam coupled to the first pintle in a manner that the first cam rotates when the first pintle rotates;
the second cam coupled to the second pintle in a manner that the second cam rotates when the second pintle rotates;

the first and second cam followers positioned between the first and second cams, and respectively abutting the first and second cams, and movably connected with each other such that the first cam follower is able to slide on the second cam follower; and the biasing member positioned between the first and second cam followers such that the first and second cam followers are biased axially by the biasing member.

2. The double-pintle hinge as claimed in claim 1, wherein the first and second cams each have a periphery and include a recess defined by the periphery, wherein the first and second cam followers each have an outer surface and include a protrusion extending from the outer surface, and wherein the first and second pintles have a first releasably retained position in which one of the protrusions is releasably engaged with the respective recess, and a second releasably retained position in which the two protrusions are releasably engaged with the respective recesses.

3. The double-pintle hinge as claimed in claim 2, with the double-pintle hinge having a fully open position and a closed position defined from the two releasably retained positions of the first and second pintles, and wherein the first and second pintles are limited to rotate between the fully open position and the closed position.

4. The double-pintle hinge as claimed in claim 3, wherein the first and second pintles respectively have an outer surface and include a first ridge extending from the outer surface, wherein the first joining member has an outer surface and includes a second ridge extending from the outer surface, and wherein the double-pintle hinge in the fully open position includes the first ridge of one of the first and second pintles releasably engaged with the second ridge.

5. The double-pintle hinge as claimed in claim 4, wherein the first ridge of the respective first and second pintles has two distal ends spaced radially and a curved outer edge joining the two distal ends.

6. The double-pintle hinge as claimed in claim 4, wherein the outer surface of the first joining member includes a third ridge extending therefrom adapted to releasably engage with the other first ridge.

7. The double-pintle hinge as claimed in claim 2, wherein the first and second cam followers each have a L-shaped body and include a slot recessed in a first extension of the body and a tab protruded from a second extension of the

body, and wherein the slot and the tab of one of the first and second cam followers respectively engage with the tab and the slot of the other of the first and second cam followers when the first and second cam followers are connected.

8. The double-pintle hinge as claimed in claim 7, wherein the protrusion on each of the first and second cam followers is located on the first extension of the body thereof, wherein the first and second joining members include a first projection and a second projection extending therebetween, wherein the first and second cam followers are sandwiched between the first projection and the second projection, with the second extension of the body of the first cam follower being movable and abutting the first projection, and with the second extension of the body of the second cam follower being movable and abutting the second projection.

9. The double-pintle hinge as claimed in claim 8, wherein the first and second projections are defined by two walls of one of the first and second cam followers.

10. The double-pintle hinge as claimed in claim 8, wherein each of the first and second cam followers includes the body thereof having two lateral edges and includes the protrusion extending therefrom located between the two lateral edges, wherein the two lateral edges of each of the first and second cam followers are sandwiched between inner surfaces of the first and second joining members, and wherein the two lateral edges of each of the first and second cam followers are defined by two lateral sides of the first extension as well as two lateral sides of the second extension.

11. The double-pintle hinge as claimed in claim 7, wherein the first and second cam followers each include a cavity to hold a distal end of the biasing member.

12. The double-pintle hinge as claimed in claim 1, wherein the first and second pintles each include a plurality of elastomeric members engaged therewith, and wherein the plurality of elastomeric members on the first pintle are restrained between one of the first and second joining members and a first retainer and the plurality of elastomeric members on the second pintle are restrained between one of the first and second joining members and a second retainer.

13. The double-pintle hinge as claimed in claim 12, wherein the first retainer and the first pintle are in thread engagement, and wherein the second retainer and the second pintle are in thread engagement.
